UNITED STATES PATENT OFFICE

JUANITA B. DICKSON, OF LOS ANGELES, CALIFORNIA

DESIGN FOR A COMBINATION BRASSIÈRE AND GIRDLE

Application filed March 23, 1931. Serial No. 39,209. Term of patent 7 years.

To all whom it may concern:

Be it known that I, JUANITA B. DICKSON, a citizen of the United States, residing at Los Angeles, in the county of Los Angeles and State of California, have invented a new, original, and ornamental Design for a Combination Brassière and Girdle, of which the following is a specification, reference being had to the accompanying drawings, forming part thereof.

I claim:

The ornamental design for a combination brassière and girdle substantially as shown.

JUANITA B. DICKSON.
